UNITED STATES PATENT OFFICE.

ABE GOLDBERG, OF CHICAGO, ILLINOIS.

DESIGN FOR A SAVINGS-BANK.

53,579.

Specification for Design.

Patented July 15, 1919.

Application filed December 31, 1918. Serial No. 269,155. Term of patent 14 years.

To all whom it may concern:

Be it known that I, ABE GOLDBERG, a citizen of the United States, and a resident of Chicago, in the county of Cook and State of Illinois, United States of America, have invented a new, original, and ornamental Design for a Savings-Bank.

Reference is to be had to the accompanying drawings in which—

Figure 1 is a plan view of a savings bank embodying my new design;

Fig. 2 is an elevation; and

Fig. 3 is an elevation of the opposite side from Fig. 2.

I claim:

The ornamental design for a savings bank, as shown.

ABE GOLDBERG.
